UNITED STATES PATENT OFFICE.

MORRIES WELSH, OF QUINCY, MASSACHUSETTS.

INDICATOR-LOCK.

SPECIFICATION forming part of Letters Patent No. 289,196, dated November 27, 1883.

Application filed April 16, 1883. (Model.)

To all whom it may concern:

Be it known that I, MORRIES WELSH, of Quincy, in the county of Norfolk and State of Massachusetts, have invented a new and useful Improvement in a Combined Door-Lock and Annunciator, which will, in connection with the accompanying drawings, be herein-after fully described, and specifically defined in the appended claims.

10 The object of my invention is to provide an annunciator or indicating device in combination with a door-lock which shall, by the act of bolting or locking a door to which the same is attached, automatically bring into view upon the outside of the door an indicator or lettered sign, showing that the room, or apartment into which such closed door opens is occupied or unoccupied, as the case may be, thus avoiding the necessity of approaching the 15 door and manipulating the knob to ascertain that fact, it being particularly designed for use on water-closet doors in railroad-cars, hotels, &c.; and the invention consists in the construction and combination of the divers 20 devices embodied therein, as is hereinafter 25 more fully described and claimed.

In the accompanying drawings, Figure 1 is a side elevation of a common mortise-lock, having a portion of the case or shell broken away, so as to show more clearly my improvement as applied thereto. Fig. 2 is a similar view, showing the devices disclosed in Fig. 1 in a different position, with the indicator raised to show through the aperture in the door. Fig. 3 is a similar view of the lock, in which the devices operated from the inside of the room are in part removed, to more 30 clearly disclose the similar devices which are operated from the outside. Fig. 4 is a central vertical section taken longitudinally through one of the knobs and a portion of the spindle and devices actuated thereby, and as on line *x*, Fig. 1, and also showing the outside knob in elevation.

35 The lock shown in said views is, with the exceptions hereinabove named, of the usual construction of such mortise-locks, containing two bolts, one operated by a key and the other by a spring in one direction and by the 40 knob-spindle and its devices in the other direction, in the usual manner. The key-bolt is 45 not shown, it being concealed by that portion

of the case or shell *a* in which the key-hole is shown, and has no practical connection with my improvements, and my improvements are 50 not necessarily confined to the form or kind of lock shown. In the upper portion of the lock, the interior of which is disclosed by the breaking away of the shell *a* in the views given, is located a bolt, *b*, which is moved 55 outward by the contractile force of a spring, *c*, attached at one end to the bolt, as shown, and at its opposite end to a boss, *d*, centrally located in the case, and internally threaded to receive the screw which secures the shell *a* in 60 place as a cover to the works. The outer end of bolt *b* is preferably, when used in connection with my improvements, not formed with a bevel or oblique "nosing," so as to be operated 65 by the act of closing the door, in the usual manner, but is of full thickness at the end, as shown at A, Fig. 3, or so formed that it will strike squarely against the plate upon the door frame or jamb, and not be thereby forced 70 inward on closing the door in the usual manner, the object in this being to render it necessary to turn the inside knob to fully close 75 the door, and thus bring the indicator into view, and to also turn the outside knob to close the door when leaving, and thus change 80 or conceal the indicator, as will be more fully explained. At its inner end said bolt is slotted at *e*, into which slot projects a pin, *f*, secured in a lever, *g*, which is pivoted at *h*, all 85 in the usual manner, the slot *e* being of sufficient extent toward the outer end of the bolt to allow the bolt to be forced inward far enough to close the door without its disturbing the 90 devices which are actuated by the knobs and their connections. A lever, *i*, mounted upon the square bar or knob-spindle, is thereby 95 actuated in the usual manner, so that its arm *j* will force the lower end of lever *g* backward when the inside knob is turned, and thus, when the door is bolted, withdraw bolt *b* from the bolt-plate on the door-jamb against the resistance of spring *c*. There is nothing new in actuating the bolt in this manner.

I will now describe in detail one method of carrying my invention into effect as applied to the form of lock shown. I combine with said lock a vertical indicator-slide, *k*, consisting of a narrow metallic plate or bar, the front edge of which is supported and guided by the

face-plate *l*, and being otherwise secured in position by the caps *m m* and the edge of shell *a*, to which said caps are attached. Said plate *k*, upon the inner side, is provided with lugs 5 *n o*, between which the outer end of a lever, *p*, operates to move said slide upward, while the end of a lever, *q*, engages the plate and lug *n* in a notch, *r*, formed therein, to hold the plate in position when the indicator is ele- 10 vated, so as to be seen from the outside through an aperture in the door, and when said plate is released by lever *q* a spring, *s*, attached to the plate at one end and at its opposite end to cap *m*, by its contractile force, draws said 15 plate downward.

Formed as a part of or attached to the upper end of plate *k* is a right-angled extension, *t*, which serves as an indicator or annunciator plate, upon which may be lettered the word 20 "Occupied," or any other suitable word or words or sign to impart the information that the closet or apartment upon the door of which it is so shown is occupied or unoccupied, such indicating-sign being, as before stated, ar- 25 ranged to be seen from the outside through an aperture made in the door for that purpose, as shown by the dotted lines surrounding said sign in Fig. 2, in which view the indicator is shown as raised and secured in position to be 30 seen through the door, as stated.

Instead of constructing the knob-spindle in one piece or bar extending from one knob to the other, so that the movement of one knob imparts a corresponding movement to the 35 other in the usual manner, I make said spindle in two parts, dividing the spindle trans- versely midway between the knobs, as shown in Fig. 4. Part *u* is attached to knob *w*, and part *v* to the knob *x*, each being free to 40 turn on the axis of its spindle independently of the other, while inseparably connected linearly by a wire, *y*, extending from a chamber in spindle *v*, where the wire is formed with an enlarged head, through a longitudinal passage 45 in the spindles to spindle *w*, in which it is threaded, thus securing the knobs, against separation when serving simply as a door- pull. I also duplicate the usual spindle-lever, employing two levers, *i* and *i'*, Fig. 4, each 50 having a central hole formed to receive the spindle, and being provided with arms *j* and *j'*, to act upon the duplicate levers *g* and *g'*, which are both pivoted to the lock-case at *h*. The spindle-lever *i* has its square aperture 55 closed upon the side adjacent to lever *i'*, except a small opening for the passage of wire *y*, thus keeping the inner ends of the two spindles entirely separate and apart, and free to turn independently with their respective 60 knobs and levers. The lower end of lever *g* acts against a shoulder, *f'*, formed on the inner side of bolt *b*, as indicated by a dotted line in Fig. 3, while lever *g* acts upon said bolt through pin *f*, operating in slot *e*, as be- 65 fore stated. The levers *g* and *g'*, through their short arms, act upon levers *p* and *q*, as shown in Fig. 2, lever *g* being moved by spindle *v*,

acting through lever *i*, when turned by knob *x* on the inside of the door, and lever *g'* being moved by spindle *u*, acting through lever *i'*, 70 when turned by the knob *w* on the outside of the door. The outer end of bolt *b* not being beveled, as before stated, and thus rendered automatically self-locking, the door cannot be closed from within or without without first 75 turning either one or the other of the knobs, and thereby affecting the position of the indicator. When the door is thus closed by turning the outside knob, then the indicator is dropped, leaving the aperture in the door 80 vacant, or, as may be preferred, bringing another portion of the indicator-plate into view, lettered or marked to signify that the closet or apartment into which the door opens is un- 85 occupied. When the occupant leaves the closet, simply swinging the door to after him, it will be held ajar by the projecting spring- bolt *b* and until the outside knob is turned to fully close and bolt the same the locking devices actuated by said knob and its spin- 90 ple *u*, and the indicator-slide will be in the 95 respective positions shown in Fig. 3, when, by turning knob *w* to force bolt *b* inward against the resistance of spring *c*, to fully close and secure the door, the spindle-lever *i'* will act, through its arm *j'*, against lever *g'*, which, acting against shoulder *f'*, will move bolt *b* inward, and at the same time the short 100 arm of lever *g'* will act upon the long arm of lever *q*, thereby rocking the lever upon its pivot and withdrawing its outer end from notch *r* in the indicator-lug *n*, thus releasing the plate *k* from the upward support of lever *q*, when the spring *s* will draw the plate 105 downward, thereby changing the indicator so as to impart the information that the closet is vacant, and while in this condition any further manipulation of the outside knob in opening and closing the door exclusively from that side will not affect the position of the 110 annunciator. Said plate *k* and lever *q* will re- 115 main as shown in Fig. 1. But when the door is thus opened from the outside a per- son entering the closet must turn the inside knob, *x*, in order to fully close and bolt the 120 door, and in so doing spindle-lever *i*, Fig. 2, will be rocked so that its arm *j* will act upon the lever *g*, and said lever, through its pin *f*, operating in slot *e*, will move bolt *b* inward against the force of its spring *c*, thus enabling 125 the door to be fully closed, and at the same time the short arm of lever *g* will act upon the short arm of lever *p*, whose long arm ex- 130 tends under lug *o* on plate *k*, and thereby raise plate *k* and its indicating-arm *t* until 135 the indicator, or that portion of it which an- nounces that the closet is occupied, stands opposite the aperture in the door, where it may be seen from the outside, and as the in- dicator is thus raised the notch *r* is moved 140 up so that the end of lever *q* is made to en- gage the same by the contractile force of its spring *s*, secured thereto at one end and at its 145 opposite end attached to the lock-case. Thus

turning the inside knob places the several parts in the positions shown in Fig. 2, and they can be displaced only by turning the outside knob, as hereinbefore stated.

5 It is obvious that many modifications in the details of construction may be made in carrying my invention into effect. Therefore,

Having described one practical method of accomplishing the object of my invention, I 10 claim—

1. In a door-lock, *a*, and in combination with suitable coacting devices for moving the bolt *b* thereof, a knob-spindle divided transversely into sections *u v*, united by a pivotal 15 longitudinal connection, *y*, whereby the two sections are secured against lineal separation while being free to rotate independently, substantially as and for the purposes specified.

2. The combination of knob-spindles *u v*, 20 provided with a lineal connection, *y*, levers *i* and *i'*, formed to receive said spindles and to be actuated thereby, and with a partition 25 upon one of said levers at the base of its spindle-socket, to prevent contact of the inner ends of said spindles with each other, bolt *b*, and indicator *t*, constructed and arranged to be actuated thereby, all substantially as and for the purposes specified.

3. The knob-spindle *v*, the coacting levers *i g p*, the locking-lever *q*, provided with an actuating-spring, *z*, and the indicator-slide *k*, the said parts being so constructed, combined, and relatively arranged to operate together 30 that spindle *v*, when seated in lever *i* and rotated, as described, will actuate said lever so that it will in turn operate lever *g*, and thereby withdraw the bolt and at same time to

act upon lever *p*, and thereby elevate slide *k*, when lever *q*, actuated by the contractile force of its spring *z*, will engage the notch 40 in said slide and thus lock the same in such elevated position, substantially as described, and for the purposes specified.

4. The knob-spindle *u*, the coacting levers *i' g'*, and *q*, the bolt *b*, and the indicator-slide 45 *k*, provided with an actuating-spring, *s*, the said parts being so constructed, combined, and relatively arranged to operate together that spindle *u*, when seated in lever *i'* and rotated, as described, will actuate said lever 50 so that it in turn will operate lever *g'* to withdraw the bolt, and at same time to act upon lever *q* to release the same from the notch in the indicator-slide, when said slide *k* and its indicator or signal will be lowered 55 by the contractile force of the spring *s*, substantially as before described, and for the purposes specified.

5. The combination, with a door-lock and signal, operatively connected by the means 60 substantially as described, of a locking-bolt having a square or non-beveled nose or locking end, whereby it is made necessary, in order to close and bolt the door therewith, to manipulate the bolt-actuating knob, whereby 65 the requisite movement and change of the connected signal is surely effected whenever the door is so bolted or unbolted, as and for the purposes specified.
